UNITED STATES PATENT OFFICE

143,581

DESIGN FOR A COMBINED CAP AND DISPENSER FOR JARS AND THE LIKE

Samuel A. de Waltoff, New York, N. Y., assignor to Deleit Enterprises, Inc., Los Angeles, Calif., a corporation of California

Application May 18, 1945, Serial No. 119,611

Term of patent 14 years

(Cl. D58—26)

To all whom it may concern:

Be it known that I, Samuel A. de Waltoff, a citizen of the United States of America, residing at New York, county of New York, and State of New York, have invented a new, original, and ornamental Design for a Combined Cap and Dispenser for Jars and the like, of which the following is a specification, reference being made to the accompanying drawing, forming a part thereof, in which

Fig. 1 is a side elevational view of a combined cap and dispenser for jars and the like, showing my new design.

Fig. 2 is a perspective view of my design as shown in Fig. 1.

Fig. 3 is a sectional view on line 3—3 of Fig. 1; and

Fig. 4 is a view similar to Fig. 1, with the piston portion at an intermediate point on the threaded item.

I claim:

The ornamental design for a combined cap and dispenser for jars and the like, as shown.

SAMUEL A. DE WALTOFF.
